(57) **CLAIM**

The ornamental design for a electrophoresis instrument, as shown and described.

DESCRIPTION

FIG. 1 is a perspective view of an electrophoresis instrument showing our new design;

FIG. 2 is a front elevational view thereof, shown with the cover in place;

FIG. 3 is a rear elevational view thereof;

FIG. 4 is a right side elevational view thereof; and,

FIG. 5 is a left side elevational view thereof.

The surfaces or portions of the article not shown in the drawing or described in the specification forms no part of the claimed design.
